UNITED STATES PATENT OFFICE.

SPENCER C. CARY, OF BROOKLYN, NEW YORK, ASSIGNOR TO CARY MANUFACTURING COMPANY, OF BROOKLYN, NEW YORK, A CORPORATION OF NEW YORK.

MEANS FOR BINDING PACKING BOXES.

Application filed December 3, 1918. Serial No. 265,084.

To all whom it may concern:

Be it known that I, SPENCER C. CARY, a citizen of the United States, residing at the city of New York, borough of Brooklyn, 5 county of Kings and State of New York, have invented a certain new and useful Means for Binding Packing Boxes, of which the following is a specification.

This invention is a device for use in binding shipping packages, usually wooden boxes, the object in view being to facilitate the operation of placing a binder around the packing box, and, more particularly, to 10 position said binder in an accurate relation 15 to the end portion of said box.

The art of binding wooden packing boxes has progressed to the point where it is customary for medium sized packages to have the binder applied backwardly about two 20 inches or more from the end of the case. The binder is drawn to place tension thereon by the aid of a stretching tool, the latter acting to draw the binder so tightly into contact with the case as to in effect 25 compress, more or less, the wooden slats of the case, such application of the binder compensating to a material degree for the natural shrinkage of the wood. Manifestly, the quick adjustment of a binder around the 30 box will result in the binder being more or less irregularly positioned thereon when applied backwardly from the end of the box, so that the binder is not spaced throughout its length uniformly from the end face of 35 the box, but, on the contrary the binder extends irregularly so as to be further from the end on one side and closer to the end on the other side of the box, as a result of which the binder cannot be evenly stretched 40 by a tightener and the bound box presents a slovenly appearance even though the binder may be applied by a skilled workman.

The use of my invention obviates the 45 foregoing and other difficulties inherent in the hand application of binders where no appliances are available or used.

One problem connected with the binding of wooden packing boxes is the control of 50 the coil of strapping or wire necessarily used in the operation of binding. The flat metal strap is usually supplied to the trade in a coil which is suspended so it can be drawn off freely in the required length, 55 whereas the wire used is also in a bundle

or coil wound more or less irregularly. Owing to the flexibility of the strap or wire, it becomes slack and beyond control particularly at the free end so that the bundle or coil will of itself unwind to a great extent 60 so as to become entangled, resulting in waste of the material and loss of time in handling it. According to this invention, means are employed for mounting the binding material in a particular relation to the position 65 occupied by the packing box during the application of the binder thereto, means are provided, also, for retaining the box in the desired position, and, further, means are provided for restraining the binder, (either 70 strapping or wire) from unwinding at the leading end thereof, all of which means contribute to a marked extent in the operation of uniformly and quickly positioning a binder upon the box so it will be spaced 75 regularly from the end of such box.

Instead of drawing the binder from a coil of strapping or wire, I may use the binder in cut lengths particularly in establishments where it is required to bind a large number 80 of boxes uniform in size. To this end I use a box-supporting member, a gage to determine the position of the box upon said member, and a channeled member attached to the box-supporting member and operating as a means for locating a binder in a 85 definite relation to the box, said channeled member being adapted for receiving a binder of a desired length and said channeled member having a shiftable stop for determining the position of the binder. 90

Other features and advantages of the invention will appear from the detailed description taken in connection with the drawings, wherein—

Fig. 1 is a front elevation of a device for binding packages embodying this invention and showing more particularly means for mounting a reel of flat metal strapping in cooperative relation to certain work-locating devices. 95

Fig. 2 is a vertical section in the plane of the dotted line 2—2 of Fig. 1 looking in the direction of the arrow.

Fig. 3 is a plan view of a portion of the 105 box-supporting member showing on an enlarged scale the shiftable element of the work-locating device.

Fig. 4 is a vertical section on the line 4—4 of Fig. 3.

Fig. 5 is an elevation partly in section illustrating another embodiment of the invention wherein provision is made for mounting a reel of wire and for straightening the wire as it is supplied to the package to be bound.

Fig. 6 is a cross section on the line 6—6 of Fig. 5 illustrating one form of the wire directing means.

10 Figs. 7, 8 and 9 are views in plan, elevation and detail section of another embodiment of the invention wherein provision is made for the use of binders cut to lengths and the parts of which device are so related to each other as to locate the box and the binder in definite positions so as to apply the binder a determined distance backwardly from the end of the box and spaced uniformly and regularly from said end.

20 The box-supporting member is shown in the drawings as a table A supported at a suitable height by legs a. In a constructional form shown, the table is provided with depending sides a' adapted to form an enclosure or boxing within which the legs are packed for shipment or storage. The sides are reinforced by corner irons or straps a² which provide bearings for the holding screws a³ adapted to enter the legs for the purpose of holding them fixedly in position in order to support the table at a desired height.

30 A reel X of flat coiled strapping is wound upon a spool a, and this reel is mounted adjacent to the box-supporting member so as to occupy a definite relation to a projecting end portion of the box to be bound. As one means for mounting the reel I provide a bracket B consisting of an upright portion b and a horizontal arm b', the latter being provided with a vertically ranging slot c shown in dotted lines in Fig. 1 and in full lines in Fig. 2. The vertical portion of the bracket is fastened by bolts c' to a fixture 40 C which is secured firmly by bolts c² to an end portion of the table, see Fig. 2.

45 D is an arbor on which is loosely mounted a spool of the coiled strapping. Said arbor is provided intermediate its ends with a collar d, the respective end portions of the arbor being externally threaded, see Fig. 2. An end portion of the arbor passes through the vertical slot c of the bracket and on one end of this arbor is a binding nut d', the latter operating to clamp the shouldered portion d of the arbor fixedly to the arm b' of the bracket, whereby the nut may be unscrewed for the purpose of raising or lowering the arbor within the slot c and thus provide for a vertical adjustment of the reel of coiled strapping in order to bring said strapping into proper relation to the top of the box which is to be bound with the strapping.

55 The spool of the coiled strapping is fitted

loosely on the arbor to rotate freely thereon so that the operator can draw the strapping from the reel as it is required to be paid out in order to position the strapping around the box indicated at Y. To restrain the coil 70 from unwinding too freely, it is desirable, or in fact necessary to place tension upon the reel, and in the constructional form illustrated in Figs. 1 and 2 I employ a gripping mechanism positioned for contact with

75 the edge portions of the strapping on the respective sides of the reel. The gripping device embodies two members E E' which are perforated substantially centrally there-

80 of in order to fit loosely upon the arbor, whereby said members are mounted upon said arbor in position for frictional engagement with the edge portions of the coiled strapping. The member E is fitted on the

85 arbor for contact with the shoulder d there- of, and at the lower portion of said member E it is provided with a lug e extending out- wardly from the member, said lug being

90 provided with an aperture in which is loose- ly fitted the lower portion of the companion member E', (see Fig. 2). On the threaded end of the arbor is screwed a nut e' which is adapted to be tightened in order to force the member E into contact with the shoul- 95

der d, thereby gripping the coil X between the cooperating members E E'. One of the

99 members, as E', is provided with a hand- grip e² for shifting the position of the grip- 100

ping device relatively to the reel, but, if de- 105

100 means may be provided for retaining the gripping device in the vertical position shown, although I have not considered it necessary to illustrate said retaining means 105

for the reason that it is obvious to those skilled in the art.

110 For the expeditious application of the strapping to the box Y it is desirable that the box be positioned upon the table A for an end portion of said box to project a pre- 115

determined distance beyond the plane of the margin of the table and the reel of binding material. Of course, the boxes may vary in

size, but in large establishments it is cus- 115

120

120 packed. To locate the box in a definite relation to the reel, as well as to provide for the adaptation of my invention to boxes of dif- 125

125 ferent sizes, I employ work-locating means 130

130 illustrated more particularly in Figs. 2, 3 and 4 of the drawings. The table A is pro- 135

guide is provided with a longitudinal slot g , and within this guide is fitted a gage G provided at one end with a face plate g' . The gage is slidable to different operative positions within the channelled guide and it is retained in a desired position by a clamping bolt H , the head h of which is adapted for movement in the recess f . The bolt passes through the slot g of the channelled guide and an aperture of the shiftable gage, and the upper threaded end of said bolt is provided with a clamping nut h' whereby the bolt and nut cooperate in clamping the shiftable gage to the desired position on the channelled guide.

The operation may be described as follows:—

The reel of coiled strapping is placed within the gripping means, for which purpose the nut e' is unscrewed from the arbor and the member E' is disconnected from said arbor and from the flange e of the member E , after which the spool x of the reel is slipped over the arbor, the member E' is replaced and the nut e' is screwed on the arbor so as to draw the members E E' into frictional engagement with the edges of the reel and with the collar d of the arbor. The reel may be raised or lowered by partly unscrewing the nut d' and shifting the arbor in the slot c of the bracket, after which the nut d' is again tightened so as to clamp the arbor fixedly in position. It is to be noted that the means for clamping the arbor adjustably to the bracket are independent of the means for gripping the members E E' into contact with the edges of the reel, although a single arbor is used as the means for attaching the reel to the bracket and as the means for mounting the gripping members and the reel so as to apply the required tension to said reel. A box Y is positioned upon the table for an end portion of said box to extend beyond the margin of the table, as shown in dotted lines in Fig. 2. In applying the strapping to the box the leading end of the strap is drawn from the reel and passed around the box, as shown in Fig. 1, the end portion of the strap and an intermediate portion of said strap being engaged with certain grippers of a stretching device indicated generally by the reference character T in Fig. 1. The strapping having been engaged with the stretcher the operator should cut the strapping at a point between the grippers of the stretcher, and thereafter the stretcher is operated so as to impart relative movement to the grippers, thereby drawing the band tightly around the box, after which the end portions of the band are fastened together, preferably by the aid of a sealing device.

It should be stated that the box is positioned upon the table through the agency

of the gage G , the latter being moved in the channeled plate so as to accurately locate the successive boxes with respect to the reel and the table.

The mechanism herein disclosed provides for the accurate application of the strapping material upon boxes of uniform size, for the reason that the gage cooperates with the table in locating the successive boxes, and the reel provides a convenient source of supply of the binding material in such relation to the boxes that the operator is not required to exercise skill or care in placing the strapping material around the boxes, it being noted that the strapping is so positioned upon each box that all portions of the strapping are at the same distance from that end portion of the box which projects beyond the table. After applying and securing a band near one end portion of a box, said box is reversed upon the table, and a second band is applied to the same box near the opposite end portion thereof.

As heretofore described, the invention embodies means for handling coiled strapping, but my invention may be embodied in means for applying wire as the binding material to the boxes. The box-supporting means is the table provided with the gage, as heretofore described, but in lieu of the bracket B , the arbor and the gripping means heretofore described, I employ the following devices:

Attached fixedly to a side portion of the table is a member I one portion of which extends above the table, and another portion depends from the table. The depending portion of the member is provided with a foot i which carries a vertical post J . Said post is provided at its upper portion with a bearing j for the axle x' of a reel of wire X' . Said post is provided with a longitudinal slot j' in which is slidably fitted a saddle L , the latter being adapted for frictional contact with a peripheral portion of the wire reel. The saddle is lifted within the slot of the post by a spring l so that the saddle is normally in contact with the reel and acts as a brake to preclude such rapid or free rotation of the reel as will tend to uncoil the wire therefrom. The wire passes upwardly from the reel to and around a direction sheave m which is loosely mounted in the horizontal portion M of the member I . The wire drawn from a reel is not in a straight condition and it is desirable to straighten the wire as it passes from the reel to the box. Accordingly, I may use either or both of the wire-straightening devices illustrated in Fig. 5. One of said devices is a tube O supported on the horizontal portion M of the member I , said tube being adjacent the direction sheave m .

m and is horizontally positioned intermediate the sheave and the box. Another of the wire-straightening devices consists of rollers *P* loosely journaled on the member *I* or its horizontal portion *M*, said rollers being staggered relatively to each other so that the wire will pass between and in contact with the rollers in a manner to straighten said wire as it is drawn from the reel and prior to its application to the box.

Although I have shown and described my invention as adapted for utilizing binders, either in flat strap or wire form, by drawing the same from a reel or coil, yet it is to be understood that the principle of the invention may be utilized in connection with binders cut to a determined length, and in Figs. 7, 8 and 9 there are illustrated one practical embodiment of this part of the invention.

The box supporting member is a table *A'* provided as heretofore described with a box locating means in the form of a channeled and slotted guide member *F'* set flush with the top surface of the table and a shiftable gage *G'* slidably fitted to the member *F'* so as to be held in fixed positions thereon by the binding screw, all as shown more clearly in Figs. 3 and 4.

In lieu of means for supporting a coil or reel in definite relation to the table, this part of my invention embodies means for locating a binder, cut to length, in a definite relation to the box to be bound. Accordingly, I employ a channeled rail *Q* attached to the table so as to lie substantially flush therewith, said rail being positioned crosswise of the guide member *F'*. The rail consists of suitable material, preferably metal, provided with a channel or groove *q* in the top surface thereof, said rail being of a length to receive and contain the cut binder to be applied to the package. As shown, the rail is attached to the table at or near the end of the latter, the opposite ends of said rail *Q* extending beyond the respective sides of the table. A stop *R* is attached to the channeled rail to afford an abutment for the end of the binder when it is placed in said channel, and this stop is shiftable lengthwise of the rail, being held in one of a desired number of positions by a binding screw *r*.

In using this part of the invention, a binder, composed of flat strapping or wire,

is cut in lengths suitable for application to the boxes, the latter being of one size. The gages *R* and *F'* are adjusted to suit the size of the boxes, and thereafter a binder is placed in the channel of the rail *Q* and a box is placed upon the table and crosswise of the rail and the binder therein, the binder abutting the gage *R* and the box resting against the gage *F'*, whereby the box and the binder are located in definite relation to each other. The binder is bent or folded around the box, as shown in dotted lines in Fig. 8, the end portions of said binder are engaged by the stretching device, the latter is operated to place tension upon said binder, and the binder is secured or sealed.

Having thus fully described the invention, what I claim as new and desire to secure by Letters Patent is:—

1. A package binding apparatus embodying a work-supporting member, and a plurality of work-locating devices supported by said member, one of said devices being operable for determining the position of a package and the other being operable for locating a binding material in a definite relation to the package, said binder-locating device being positioned crosswise of the package locating device.

2. A package binding apparatus embodying a work-supporting member, a package-locating gage mounted on said member, and a binder-locating member also mounted on the member and positioned crosswise of the package-locating gage for locating the binding material in a definite relation to the position of the package, said package-locating gage being shiftable at will toward or from the binder-locating member.

3. A package binding apparatus embodying a work-supporting member, a package-locating gage mounted on said member, and a binder-locating member also mounted on the member and positioned crosswise of the package-locating gage for locating the binding material in a definite relation to the position of the package, said binder-locating member comprising a channeled rail and a gage shiftable on the channeled rail toward or from the direction of movement of the package-locating gage.

In testimony whereof I have hereunto subscribed my name this 30th day of November, 1918.

SPENCER C. CARY.
